FREE FLOW WALL CLEANER

Luther J. Herndon and Jack B. Queen, both of Duncan, Okla., assignors to Halliburton Company, Duncan, Okla., a corporation of Delaware

Filed Apr. 27, 1962, Ser. No. 190,719

9 Claims. (Cl. 166—173)

This invention relates to a well bore wall cleaner and, in particular, is directed to a cleaner of this type which presents a minimal amount of resistance to fluid flow past the cleaner.

There are numerous operations and processes performed during the drilling and completion of a well in which it is desirable to clean the well bore wall in some manner. It has been conventional to mount scratchers on the exterior of a casing, run the casing into the well bore, and reciprocate or rotate the casing so that the scratchers abrade or scratch the well bore wall to remove the drilling mud filter cake and the like from the well bore wall.

Since a well bore is usually irregular in surface configuration and diameter it is generally desirable that the scratcher have members which are flexible in order to conform to the configuration and diameter of the well bore. There are numerous types of scratchers having flexible elements protruding outwardly with their terminal ends adapted to engage and abrade the well bore wall. However, there are certain well bore conditions wherein it is undesirable to abrade or scratch the well bore wall with a pointed element even though it is desirable to remove the filter cake from the well bore wall. In these certain conditions, this type of pointed scratcher may remove the filter cake but may also remove an excessive amount of the earth formation which may cause caving-in of part of the formation.

It is conventional to circulate the drilling mud during the scratching operation in order to carry the material, which has been removed by the scratching, to the surface of the well. Thus the drilling fluid or mud must be circulated past the scratchers in the annular space between the casing and the well bore wall. Further, when the casing is being cemented into the well bore the cement must also flow past the scratchers in a like manner. The abrading elements of many of the conventional scratchers are relatively thick in cross sectional area or are so numerous as to create a substantial restriction to the flow of fluid past the scratcher. In numerous situations, a relatively long portion of well bore wall must be cleaned and therefore numerous scratchers must be provided on the exterior of the casing. In such a situation, the resistance to fluid flow past the scratchers may be objectionably high due to the cumulative effect of the numerous scratchers used.

Accordingly it is an object of this invention to provide a novel form of well bore cleaner adapted to be mounted on a well pipe wherein the elements provided for cleaning the wall of the well bore present a minimal restriction to the flow of fluid past the cleaner and these elements.

Another object of this invention is to provide a novel form of well bore wall cleaner wherein projecting elements for cleaning the well bore wall are provided which engage the well bore wall in a line contact rather than a point contact to accomplish cleaning of the wall without objectionably gouging or abrading the wall.

A further object of this invention is to provide a novel form of well bore wall cleaner wherein loop shaped elements are provided having arcuate portions which combine to define a circle for cleaning the well bore wall. A still further object is to provide such a cleaner wherein the loop shaped elements may pivot toward the casing in-

2

dividually or together to assume the particular configuration or size of that portion of the well bore.

A more specific object of this invention is to provide a well bore wall cleaner wherein loops are pivotally mounted on a collar adapted to be mounted on a well pipe and such loops overlap one another to define substantially the circumference of a circle the size of which is varied as the loops are pivoted.

Other and more detailed objects and advantages of this invention will appear from the following description and the accompanying drawings.

In the drawings:

FIGURE 1 is a plan view of the well bore wall cleaner of this invention.

FIGURE 2 is a fragmentary sectional elevation taken substantially on the line 2—2 as shown in FIGURE 1.

FIGURE 3 is a fragmentary sectional elevation from the inside of the collar of this invention taken substantially on the line 3—3 as shown in FIGURE 2.

FIGURE 4 is a fragmentary sectional plan view taken substantially on the line 4—4 as shown in FIGURE 2.

FIGURE 5 is a sectional elevation view similar to FIGURE 2 illustrating the loops of the cleaner in their upwardly pivoted position.

FIGURE 6 is a fragmentary plan view illustrating the overlapping mounting of adjacent loops.

FIGURE 7 is a perspective view showing a modified form of this invention and illustrating the device in a hinged-open position for mounting same on a well pipe.

FIGURE 8 is a perspective view of the device of this invention mounted on a well pipe with the loops pivoted upwardly from their lowermost position.

FIGURE 9 is a perspective view of one of the loops of the modified form shown in FIGURE 7.

Referring now to the drawings, the well bore wall cleaner, generally designated 10, is provided with a generally cylindrical collar designated 11. Collar 11 may be a solid cylindrical collar adapted to be slipped onto a well pipe or the collar may be comprised of two semi-cylindrical collars 12 and 13 hinged together by hinges 14 and 15. The hinge pin of hinge 14 or hinge 15 may be removed and the semi-cylindrical collars 12 and 13 pivoted to an open position for laterally applying the cleaner 10 to a well casing, tubing or pipe. The function and configuration of collar 11 is substantially the same whether it is a solid collar or a hinged collar as shown.

The collar 11 is provided with a circumferential bead 16 which is generally V-shaped and projects outwardly from the major cylindrical portion of the collar. Since bead 16 is V-shaped it is comprised of a downwardly and outwardly projecting conical portion 17 and an upwardly and outwardly projecting conical portion 18. An internal annular hollow portion 19 is formed by the bead.

The upper conical portion 17 of the bead 16 is provided with a series of apertures 20 which are relatively uniformly spaced around the entire circumference of the bead 16, this spacing being interrupted and somewhat nonuniform at the hinges 14 and 15.

The well bore cleaner 10 is provided with a plurality of cleaner elements, generally designated 21, for engaging and cleaning the well bore wall as hereinafter described. Each of the cleaner elements 21 has a loop portion comprised of a pair of outwardly projecting arms 22 and 23 joined at their outer extremities by a circumferentially extending arcuate portion 24. As may be seen in the drawings, the arms 22 and 23 and arcuate portion 24 all lie in approximately a single plane, i.e., the plane of the loop, and this plane may be either perpendicular to or at an angle to the axis of the collar 11, as will hereinafter be described.

Each of the cleaner elements 21 is also provided with a pair of mounting bases (not numbered) for mounting

the cleaner element on the collar 11. On each cleaner element 21, one mounting base is at the inner extremity of arm 22 and the other mounting base is at the inner extremity of arm 23. Each mounting base has a connecting piece 25 extending through one of the apertures 20 and joined to an arm 22 or 23. The connecting piece 25 is joined to a lateral piece 26 which extends circumferentially or laterally within the annular hollow space 19 and is joined to an end piece 27 which extends outwardly through a separate aperture 20. As shown in the drawings, each mounting base has its connecting piece 25 extending through one aperture 20 and its end piece 27 extending through a separate aperture 20. Although it is preferred and is shown in FIGURES 3, 4 and 6 that the connecting piece 25 and end piece 27 of each mounting base extend through adjacent apertures 20 it will readily appear to those skilled in the art that by providing a longer lateral piece 26 the connecting piece 25 and end piece 27 may extend through non-adjacent apertures 20 without altering or affecting the function of the mounting base.

The arms 22 and 23 of each cleaner element 21 converge inwardly toward each other such that the connecting pieces 25 joined to each of the arms pass through adjacent apertures 20. The lateral piece 26 of each mounting base extends circumferentially away from the other mounting base of the same cleaner element 21. Each cleaner element 21 has its connecting pieces 25 extending through a pair of apertures adjacent to the pair of apertures through which the connecting pieces of next adjacent cleaner element 21 extend. Since apertures 20 are spaced relatively close together and since arms 22 and 23 of each cleaner element 21 converge inwardly toward each other, the arm 22 of one cleaner element 21 overlaps the arm 23 of the next adjacent cleaner element 21. Likewise, the arcuate portion 24 of each cleaner element 21 overlaps the arcuate portions 24 of both of the adjacent cleaner elements 21 for a substantial arcuate distance. All of the arms 22 and 23 and arcuate portions 24 on the wall cleaner 10 lie substantially in a plane perpendicular to the axis of the collar 11 when the cleaner elements 21 are in their inflexed and unpivoted position shown in FIGURES 1 and 2. Each of the arcuate portions 24 preferably have a radius of curvature equal to the radius from the axis of the collar 11 to the outer extremities of the arms 22 and 23 such that the arcuate portions 24 of all of the cleaner elements 21 combine to define substantially a circle as is shown in FIGURE 1. The circumference of this defined circle is continuous since each arcuate portion 24 overlaps the next adjacent arcuate portions.

The mounting bases of each cleaner element 21 cooperate with the edges of the apertures 20 and with the bead 16 to support each cleaner element in the radially projecting position shown in FIGURES 1 and 2 but also permit each cleaner element to be pivoted upwardly as shown in FIGURE 5. In the position shown in FIGURE 2, each end piece 27 and connecting piece 25 engages the lower edge 28 of the aperture 20 through which it passes and the lateral piece 26 engages the inner surface of the upper conical portion 17 of the bead 16 thereby supporting the loop of the cleaner element in the radially projecting position. Since two mounting bases (one from each of the adjacent cleaner elements 21) are positioned in each pair of apertures 20 the connecting pieces 25, end pieces 27, and lateral pieces 26 may actually engage such pieces of the other mounting base rather than engaging the edge 28 of an aperture 20 or the inner surface of the conical portion 17. Whether the connecting piece, lateral piece and end piece of a particular mounting base are supported by portions of the bead 16 or by like pieces of another mounting base is of no consequence since in either manner the desired support is provided. The apertures 20 are substantially greater in size than the cross section of the connecting pieces 25

and end pieces 27 so that each of the elements 21 is free to pivot upwardly as shown in FIGURE 5. The upper limit of pivoting is limited only by the lateral pieces 26 engaging the inner surface of the lower conical portion 18 of the bead 16 and the connecting pieces 25 and end pieces 27 engaging the upper edge 29 of the apertures 20. A downwardly bent portion 30 is preferably provided on the extremities of each of the end portions 27 so as to prevent the end piece 27 from passing inwardly through the aperture 20. Although this inward movement of the mounting base would be limited by the engagement of lateral piece 26 with the outer surface of a well pipe when the cleaner 10 is installed on a well pipe, the downwardly bent portions 30 serve to prevent such movement when the cleaner 10 is not on a well pipe.

The modified form of well bore wall cleaner, generally designated 10a, shown in FIGURE 7 has a hinged cylindrical collar generally designated 11a which is substantially the same as collar 11 heretofore described. Collar 11a has a circumferential bead 16a provided with apertures 20a similar to the bead 16 and apertures 20 of cleaner 10. The cleaner elements 21a have mounting bases of a configuration the same or similar to that previously described but the loop portion of the cleaner element 21a is modified from the loop portion of cleaner 21. The circumferentially extending arcuate portion 24a of cleaner element 21a is similar to arcuate portion 24 but may be longer so that the amount of arcuate overlap of adjacent arcuate portions 24a is much greater. Further, the arms 22a and 23a extending from the mounting bases to the arcuate portion 24a are curved rather than straight. The curved arms 22a and 23a permit the loop portion of cleaner element 21a to be compressed radially more easily than the straight arms 22 and 23 shown in FIGURE 1.

In operation, the well bore wall cleaner 10 or 10a is positioned on a well casing, tubing or pipe 9 as shown in FIGURE 8. The movement of the cleaner 10 or 10a along the well pipe 9 is limited by providing stop lugs or collars (not shown) on the well pipe in a conventional manner, or the cleaner may be affixed to the well pipe as by welding. Although it is not essential, it is preferred that the well bore cleaner 10 or 10a be positioned on the well pipe near a centralizer so that the cleaner elements 21 or 21a will not be compressed flat against one side of the well bore. While the well pipe 9 is run through a casing or portion of the well bore which is of smaller diameter than the diameter of the circle formed by the arcuate portions 24 or 24a, the cleaner elements 21a are pivoted upwardly as shown in FIGURE 5 to conform to the size of the casing or well bore. When the well pipe 9 is reciprocated within the well bore, the arcuate portions 24a engage the well bore wall in a line contact and clean the drilling mud filter cake, etc., from the well bore wall. If the well bore is of a smaller diameter than the circle formed by the arcuate portions 24 or 24a (as will normally be the situation) the upward movement of the well pipe 9 will cause the arms 22 and 23 or 22a and 23a to be flexed downwardly to reduce the diameter of the circle formed by the arcuate portions 24 or 24a.

It is preferred to make the cleaner elements 21 or 21a of a relatively rigid and resilient material such as steel wire although other materials may be used. With a relatively rigid and resilient cleaner element 21 or 21a the arcuate portion 24 or 24a will be adequately supported for accomplishing the cleaning or scraping of the well bore wall. Moreover, by using such a material for the cleaner elements 21 or 21a the arms 22 and 23 or 22a and 23a will return to their normal unflexed configuration upon downward movement of the well pipe 9 with respect to the well bore.

Thus it may be seen that a well bore wall cleaner is provided which adjusts to the diameter of well casing or well bore through which it is passing and which has no

pointed cleaning elements that may objectionably gouge or abrade the well bore wall. Further, it may be seen that the cleaner elements of our well bore cleaner provide a full 360° contact with the well bore wall for cleaning of same and yet the cleaner elements present a very minimal restriction to the flow of fluid past the cleaner.

Having fully described our invention, it is to be understood that we do not wish to be limited to the details herein set forth or to the details illustrated in the drawings, but our invention is of the full scope of the appended claims.

We claim:

1. In a well bore cleaner, the combination of: a collar adapted to be mounted on the exterior of a well pipe, a plurality of cleaner elements circumferentially spaced around and mounted on said collar, each said cleaner element being comprised of a relatively rigid material and having a loop portion extending outwardly from said collar, each said loop portion having a pair of arms projecting outwardly from said collar and a circumferentially extending arcuate portion joining the outermost extremities of said pair of arms, and the said arcuate portions of adjacent cleaner elements overlapping for a substantial arcuate distance to form substantially a full circle for engaging and cleaning the well bore.

2. In a well bore cleaner, the combination of: a collar adapted to be mounted on the exterior of a well pipe, a plurality of cleaner elements circumferentially spaced around and mounted on said collar, each said cleaner element being comprised of a relatively rigid and resilient material and having a loop portion extending outwardly from said collar, each said loop portion having a pair of arms projecting outwardly from said collar and a circumferentially extending arcuate portion joining the outermost extremities of said pair of arms, each of said arms being curved, and the said arcuate portions of adjacent cleaner elements overlapping for a substantial arcuate distance to form substantially a full circle for engaging and cleaning the well bore.

3. In a well bore cleaner, the combination of: a collar adapted to be mounted on the exterior of a well pipe, a plurality of cleaner elements circumferentially spaced around and mounted on said collar, each said cleaner element being comprised of a relatively rigid and resilient material and having a loop portion extending outwardly from said collar, each said loop portion having a pair of arms projecting outwardly from said collar and a circumferentially extending arcuate portion joining the outermost extremities of said pair of arms, each said loop portion overlapping the loop portions of the adjacent cleaner elements on either side thereof, and the said arcuate portions of adjacent cleaner elements overlapping for a substantial arcuate distance to form substantially a full circle for engaging and cleaning the well bore.

4. In a well bore cleaner, the combination of: a collar adapted to be mounted on the exterior of a well pipe, a plurality of cleaner elements circumferentially spaced around and mounted on said collar, each said cleaner element being comprised of a relatively rigid and resilient material and having a loop portion extending outwardly from said collar, each said loop portion having a pair of arms projecting outwardly from said collar and a circumferentially extending arcuate portion joining the outermost extremities of said pair of arms, said arms being relatively small in cross-sectional area for presenting a minimal resistance to fluid flow past said arms, and the said arcuate portions of adjacent cleaner elements overlapping for a substantial arcuate distance to form substantially a full circle for engaging and cleaning the well bore.

5. In a well bore cleaner, the combination of: a collar adapted to be mounted on the exterior of a well pipe, a plurality of cleaner elements circumferentially spaced around said collar, each said cleaner element

being comprised of a relatively rigid and resilient material and having a loop portion extending outwardly from said collar, each of said cleaner elements being pivotally mounted on said collar for free movement of said loop portion from a radially extending position to an upwardly and outwardly extending position, each said loop portion having a pair of arms projecting outwardly from said collar and a circumferentially extending arcuate portion joining the outermost extremities of said pair of arms, and the said arcuate portions of adjacent cleaner elements overlapping for a substantial arcuate distance to form substantially a full circle for engaging and cleaning the well bore.

15 6. In a well bore cleaner, the combination of: a collar adapted to be mounted on the exterior of a well pipe and having internally hollow means, said hollow means having apertures therethrough in circumferentially spaced relationship around said collar, a plurality of wire cleaner elements circumferentially spaced around said collar, each said cleaner element having a pair of base portions and a loop joining said base portions; each said base portion having means extending through one of said apertures, circumferentially within said hollow means, and outwardly through another of said apertures for pivotally supporting the cleaner element on said collar; each said loop portion having a pair of arms projecting outwardly from said collar and a circumferentially extending arcuate portion joining the outermost extremities of said pair of arms, and the said arcuate portions of adjacent cleaner elements overlapping for a substantial arcuate distance to form substantially a full circle for engaging and cleaning the well bore.

20 7. In a well bore cleaner, the combination of: a collar adapted to be mounted on the exterior of a well pipe and having a circumferential extending and outwardly projecting hollow bead, said hollow bead having a plurality of circumferentially spaced apertures therethrough, a plurality of wire cleaner elements circumferentially spaced around said collar, each said cleaner element having a pair of base portions and a loop joining said base portions; each said base portion having means extending through one of said apertures, circumferentially within said hollow means, and outwardly through another of said apertures for pivotally supporting the cleaner element of said collar; and said loop of each cleaner element having an outwardly projecting arm joined to each of said base portions and a circumferentially extending arcuate portion joining the outermost extremities of said two arms, each said arm and a portion of the arcuate portion joined thereto overlapping the adjacent arm and a portion of the arcuate portion of the loop of the next adjacent cleaner element, the said arcuate portions of adjacent cleaner elements overlapping for a substantial arcuate distance to form substantially a full circle for engaging and cleaning the well bore.

25 8. In a well bore cleaner, the combination of: a collar adapted to be mounted on the exterior of a well pipe and having a circumferential extending and outwardly projecting hollow bead, said hollow bead having a plurality of circumferentially spaced apertures therethrough, a plurality of wire cleaner elements circumferentially spaced around said collar, each said cleaner element having a pair of base portions and a loop joining said base portions; said base portions each having a connecting portion, an end portion, and a lateral portion joining said connecting portion to said end portion; each said base portion having the said connecting portion extending through one of said apertures, the said lateral portion extending circumferentially within said hollow bead on the collar, and the said end portion extending outwardly through another of said apertures for pivotally supporting the cleaner element on said collar for free movement of the loop portion from a radially projecting position to an upwardly and outwardly projecting position; and said loop of each cleaner element having an

outwardly projecting arm joined to each of said connecting portions and a circumferentially extending arcuate portion joining the outermost extremities of said two arms, each said arm and a portion of the arcuate portion joined thereto overlapping the adjacent arm and a portion of the arcuate portion of the loop of the next adjacent cleaner element, the said arcuate portions of adjacent cleaner elements overlapping for a substantial arcuate distance to form substantially a full circle for engaging and cleaning the well bore and the upward pivoting of

all of the cleaner elements serving to reduce the diameter of such defined circle.

9. The combination of claim 8 wherein the said arms of the cleaner elements are curved for permitting the loop portion to resiliently collapse.
